Primary Examiner — George D. Kirschbaum*Assistant Examiner* — Katherine Glennon(74) *Attorney, Agent, or Firm* — Birch, Stewart, Kolasch & Birch, LLP(57) **CLAIM**

The ornamental design for a voice recognition speaker, as shown and described.

DESCRIPTION

1. Voice recognition speaker

1.1 is a front perspective view of a voice recognition speaker;

1.2 is a front view thereof;

1.3 is a back view thereof;

1.4 is a left view thereof where the right view is a mirror image;

1.5 is a top view thereof;

1.6 is a bottom view thereof; and

1.7 is a back perspective view thereof.

The broken lines depict portions of the voice recognition speaker that form no part of the claimed design. This design is for a voice recognition speaker with a display in the center of the front portion thereof.

1 Claim, 7 Drawing Sheets(56)
